UNITED STATES PATENT OFFICE.

GEORGE F. RAMM, OF DEL MONTE, CALIFORNIA.

ATTACHMENT FOR IRONING-MACHINES.

1,351,688.

Specification of Letters Patent. Patented Aug. 31, 1920.

Application filed February 20, 1920. Serial No. 360,128.

To all whom it may concern:

Be it known that I, GEORGE F. RAMM, a citizen of the United States, residing at Del Monte, in the county of Monterey and State 5 of California, have invented new and useful Improvements in Attachments for Ironing-Machines, of which the following is a specification.

This invention relates to laundry devices, 10 particularly to machines for ironing flat work, and has for its object the provision of a shield mounted upon the delivery end of a flat work ironing machine for the purpose of protecting the operators from the 15 intense heat thrown off by the rollers and canvas apron, for shielding the eyes from the incessant glare of the white linen passing through the rollers and also for catching the lint which is constantly thrown off in 20 small particles from the material ironed.

An important object is the provision of a shield of this character which is detachably connected with the ironing machine and which is also swingably mounted so that it 25 may be swung upwardly to permit access to the roller and canvas apron and to permit removal of any accumulation of lint upon its rear side.

Another object is the provision of a device 30 of this character including a plurality of sections, each of which carries upon its rear side a detachable screen for catching particles of lint.

An additional object is the provision of a 35 device of this character which will be simple and inexpensive in manufacture and installation, which will be highly efficient in protecting the health of the operators, which will be durable in use, and which will have 40 the further advantage of practically eliminating the objections incident to working at the delivery end of an ironing machine.

With the above and other objects and advantages in view the invention consists in 45 the details of construction to be hereinafter more fully described and claimed, and illustrated in the accompanying drawings in which—

Figure 1 is a front elevation showing my 50 device in position upon an ironing machine,

Fig. 2 is a side elevation thereof,

Fig. 3 is a rear elevation,

Fig. 4 is an enlarged cross sectional view 55 through one of the sections, and

Fig. 5 is a detail perspective view of one of the brackets.

Referring more particularly to the drawings, the letter A designates the frame of a machine for ironing flat work such as sheets, pillow cases, towels, and the like. This machine includes rollers B and a traveling canvas apron C.

In carrying out my invention I provide brackets 10 which may be secured upon the frame A at the sides thereof and which extend forward from the discharge end. These brackets are formed with sockets 11 which are open at their tops and resting within these sockets is a transverse bearing member 12 which may be a shaft but which is preferably tubular and which may be formed from a pipe. In case a pipe is used it is preferable that the ends be closed by caps 13.

Suspended from the bearing member 12 is a shield structure which is formed preferably from a plurality of sections 14, each of which is formed of suitable material. Each section is provided at its lower edge with a reinforcing rod 15 about which the sheet is turned and the purpose of this rod 16 is to prevent buckling of the sheet. At its upper edge, each sheet is coiled about the bearing member 12 and riveted, soldered, or otherwise secured to provide a bead or tubular bearing portion 16 revolvably engaged 85 upon the member 12. Adjacent their lower edges the sections are provided with handles 17 whereby they may be grasped and swung into elevated position out of obstructing relation to the delivery end of the machine. 90 Upon their outer faces the sections are preferably pointed or otherwise colored with something which will be restful to the eyes of the operators.

Disposed upon the back of each section 95 is a screen 18 which includes a rectangular frame of substantially the same dimensions as the section covered by wire mesh 19. The frame is strengthened by a rod 20 which runs lengthwise through the center of the frame. 100 The screens are held in position upon these sections by means of three offset lugs 21 which extend from the back of each section and beneath which the upper edges of the frames 18 are engaged. Disposed upon the 105 backs of the sections at their lower edges are turn-buttons 22 which engage the lower edges of the frames.

In the use of the shield it will be seen that the intense heat thrown off by the rollers, 110 canvas apron, and ironed articles passing from the device will be prevented from reach-

ing the operators. It will also be apparent that the minute articles of lint constantly thrown off will engage against the screen and be caught thereby. Under ordinary conditions, that is without the use of my device, these particles of lint not only settle upon the clothing, face, and hair of the operators but are also inhaled by them and heretofore great difficulty has been experienced in retaining operators for machines of this character owing to the harmful effects of the continued inhalation of the lint and also from the exposure to the heat. It will therefore be observed that my device is a health and life saver. In case it is desired for any reason, it will be observed that the member carrying the shield sections may be lifted bodily from the brackets. It is also apparent that by turning the turn-buttons, the screens may be removed for cleaning.

While I have shown and described the preferred embodiment of my invention it is of course to be understood that I reserve the right to make such changes in the form, construction, and arrangement of parts as will not depart from the spirit of the invention or the scope of the subjoined claims.

Having thus described my invention, I claim:

1. An attachment for ironing machines comprising a shield detachably mounted upon the delivery end thereof and arranged in depending position for covering the traveling apron thereof.

2. An attachment for ironing machines comprising a pair of brackets secured upon the frame of the machine, a supporting member extending transversely of the machine and mounted upon said brackets, and a shield depending from said supporting member and swingably mounted thereon.

3. An attachment for ironing machines comprising a pair of brackets secured upon the frame of the machine at the delivery end thereof, said brackets being provided with sockets opening upwardly, a transverse supporting member detachably engaged within said sockets, and a shield depending from said supporting member and formed as a plurality of sheets of material, said sheets being swingably mounted upon said supporting members.

4. An attachment for ironing machines comprising a shield detachably mounted upon the delivery end thereof and arranged in depending position for covering the traveling apron and rollers thereof, and a wire screen mounted upon the rear face of said shield.

5. An attachment for ironing machines comprising a pair of brackets secured upon the frame of the machine, a supporting member carried by said brackets, a shield depending from said supporting member, and a wire screen detachably mounted upon the rear side of the shield.

In testimony whereof I affix my signature.
GEORGE F. RAMM.
